US00D436347S

(12) United States Design Patent
Ito et al.

(10) Patent No.: US D436,347 S
(45) Date of Patent: ** Jan. 16, 2001

(54) CONTROL DEVICE FOR ELECTRIC APPARATUS

(75) Inventors: Masafumi Ito; Haruki Takita; Yasunobu Shimizu, all of Musashino (JP)

(73) Assignee: TEAC Corporation, Tokyo (JP)

(**) Term: 14 Years

(21) Appl. No.: 29/118,761

(22) Filed: Feb. 15, 2000

(30) Foreign Application Priority Data

Oct. 22, 1999 (JP) 11-29105

(51) LOC (7) Cl. 13-03

(52) U.S. Cl. D13/164

(57) CLAIM

The ornamental design for a control device for electric apparatus, as shown and described.

DESCRIPTION

FIG. 1 is a perspective view of a control device for electric apparatus showing our new design;

FIG. 2 is a front view thereof;

FIG. 3 is a rear view thereof;

FIG. 4 is a top view thereof;

FIG. 5 is a bottom view thereof;

FIG. 6 is a left side view thereof; and,

FIG. 7 is a right side view thereof.
